UNITED STATES PATENT OFFICE.

HOMER S. ROGERS, OF MILWAUKEE, WISCONSIN, ASSIGNOR TO JOHN R. BALL, OF MILWAUKEE, WISCONSIN.

PNEUMATIC PUMP.

Application filed February 11, 1920. Serial No. 357,770.

To all whom it may concern:

Be it known that I, HOMER S. ROGERS, a citizen of the United States, residing at Milwaukee, in the county of Milwaukee and 5 State of Wisconsin, have invented certain new and useful Improvements in Pneumatic Pumps, of which the following is a specification, reference being had to the accompanying drawing, forming a part there- 10 of.

This invention relates to pneumatic pumps and the object of the invention is to improve the construction and operation of pneumatic pumps in the manner to be hereinafter described and claimed. 15

Referring to the drawing which accompanies this specification and forms a part hereof, which drawing illustrates an embodiment of this invention, the figure is a 20 vertical section of a pneumatic pump.

Referring to the drawing, the reference numeral 1 designates a pump chamber, 2 a water inlet port, 3 a water outlet port, 4 a compressed air inlet port, and 5 an air outlet 25 or exhaust port. A pipe 6, connected with any suitable source of supply of compressed air, communicates with the compressed air inlet port 4 and the flow of air into the pump chamber is controlled by a compressed air valve 7. The air outlet or exhaust port 5 is controlled by an air exhaust valve 8. The water inlet port 2 is controlled by the water inlet valve 9 and a water outlet, or check, valve 10 prevents water from 30 returning from the water discharge pipe 11 into the pump chamber.

The compressed air valve 7 and the air exhaust valve 8 are connected with a lever 12 on opposite sides of its fulcrum 13 so 40 that when one valve is closed the other valve is opened. The lever 12 is pivotally connected with a lever 14 which is pivoted or fulcrumed on the pin 15 supported by a bracket 16, the bracket 16 being clamped by a screw 45 17 to a part of the water discharge pipe 11. The lever 14 is provided with a vertically-elongated slot 18 for a bail 19 on the float 20, this construction being a lost-motion construction so that the movements of the float 50 20 will not move the lever 14 until the bail 19 contacts either with the top or the bottom of the slot 18. A vent 21, of small size as compared with the water outlet port 3, is controlled by a valve 22 and the valve 22 55 is closed by the float 20, as the float rises,

and is opened by the float, as the float drops.

The float 20 may be connected with the valve 22 by any suitable motion transmitting mechanism as, for example, a lever 23 fulcrumed on a pin 24.

The air outlet or exhaust port 5 is made large enough so that the air exhaust valve 8 will be held seated or closed by the difference between the pressure in the pump chamber and outside thereof and hold the levers 12 and 14 up in the positions illustrated by the drawing and the float 20 is made sufficiently heavy so that it will pull the air exhaust valve 8 off from its seat when the water level has fallen sufficiently 70 low in the pump chamber. The effective weight of the float 20 will, of course, be diminished in proportion to its submergence in the water and will be increased as the submergence is decreased.

The operation of the pump is as follows. The drawing shows the parts in the positions which they occupy when water has filled the pump chamber to the point where the air exhaust valve 8 has been closed and the compressed air valve 7 has been opened. Compressed air is entering the pump chamber and driving the water out through the water discharge pipe 11. The check valve 10 is open and the water inlet valve 9 and the valve 22 are closed. The bail 19 is at the upper end of the elongated slot 18. As the water level in the pump chamber is lowered, the float 20 will fall until the bail 19 engages with the lower end of the slot 18, 80 meanwhile lifting the valve 22 and opening the vent 21. The water will continue to be driven out of the pump chamber leaving more and more of the float 20 unsubmerged until the weight of the float has increased sufficiently to pull the air exhaust valve 8 off from its seat and close the compressed air valve 7. The check valve 10 will now close and the water inlet valve 9 will open and water will flow into the pump chamber and elevate the float 20 until the bail 19 engages the upper end of the slot 18 and moves the lever 14 high enough to close the air exhaust valve 8 and open the compressed air valve 7, meanwhile closing the valve 22. The water inlet valve 9 will now close and the water will be forced from the pump chamber as hereinbefore described.

The closing of the valve 22 does not prevent the closing of the air exhaust valve 8 110

because, when the air exhaust valve 8 is nearly closed the compressed air valve 7 will be nearly wide open and the rush of compressed air through the outlet or air 5 exhaust port will seat the air exhaust valve 8, the upper end of the slot 18 in the lever 14 being free to move up away from the bail 19, as will be readily understood.

The vent 21 and the valve 22 are provided 10 so that the float 20, if it begins to descend, must continue to descend to open the air exhaust valve 8 and close the compressed air valve 7 without regard to the escape of water from the water discharge pipe 11.

15 What is claimed is:

1. In a pneumatic pump, the combination 20 with a pump chamber provided with a water inlet port, a vent, a compressed air inlet port, an air exhaust port and a water outlet port, of a water inlet valve, a water 25 vent valve, a compressed air valve and an air exhaust valve, the air exhaust port being of sufficient size so that the air exhaust valve will be retained closed by the differ-

chamber and outside thereof, the water vent valve being connected with a float to be opened as the float descends and the float being connected with the air exhaust valve and being sufficiently heavy to force the air 30 exhaust valve from its seat as the float descends.

2. In a pneumatic pump, the combination 35 with a pump chamber provided with a water inlet port, a water vent, a compressed air inlet port, an air exhaust port and a water outlet port, of a water inlet valve, a water vent valve, a compressed air valve and an air exhaust valve, the air exhaust port being of sufficient size so that the air 40 exhaust valve will be retained closed by the difference between the pressure in the pump chamber and outside thereof, the water vent valve being connected with a float and the air exhaust valve being connected with the 45 float by a lost-motion construction.

In witness whereof I hereto affix my signature.

HOMER S. ROGERS.
